CLAIM

The ornamental design for a magnetic construction part as shown and described.

DESCRIPTION

FIG. 1 is a top perspective view of a first embodiment of the magnetic construction part;

FIG. 2 is a bottom perspective view of the first embodiment of the magnetic construction part shown in FIG. 1;

FIG. 3 is a top plan view of the first embodiment of the magnetic construction part shown in FIG. 1;

FIG. 4 is a bottom plan view of the first embodiment of the magnetic construction part shown in FIG. 1;

FIG. 5 is a front elevational view of the first embodiment of the magnetic construction part shown in FIG. 1;

FIG. 6 is a rear elevational view of the first embodiment of the magnetic construction part shown in FIG. 1;

FIG. 7 is a right side elevational view of the first embodiment of the magnetic construction part shown in FIG. 1, the left side elevational view being a mirror image thereof;

FIG. 8 is a top perspective view of a second embodiment of the magnetic construction part;

FIG. 9 is a bottom perspective view of the second embodiment of the magnetic construction part shown in FIG. 8;

FIG. 10 is a top plan view of the second embodiment of the magnetic construction part shown in FIG. 8;

FIG. 11 is a bottom plan view of the second embodiment of the magnetic construction part shown in FIG. 8;

FIG. 12 is a right side elevational view of the second embodiment of the magnetic construction part shown in FIG. 8, the left side elevational view being a mirror image thereof;

FIG. 13 is a front elevational view of the second embodiment of the magnetic construction part shown in FIG. 8; and,

FIG. 14 is a rear elevational view of the second embodiment of the magnetic construction part shown in FIG. 8.

(Continued)

The broken lines in the drawings show portions of the magnetic construction part that form no part of the claimed design.
